UNITED STATES PATENT OFFICE.

VANNEVAR BUSH, OF MEDFORD, MASSACHUSETTS, ASSIGNOR TO AMERICAN RADIO & RESEARCH CORPORATION, OF MEDFORD, MASSACHUSETTS, A CORPORATION OF DELAWARE.

TRANSFORMER.

1,342,250.

Specification of Letters Patent. Patented June 1, 1920.

Application filed May 5, 1917. Serial No. 166,729.

To all whom it may concern:

Be it known that I, VANNEVAR BUSH, a citizen of the United States, residing at Medford, in the county of Middlesex, and 5 State of Massachusetts, have invented a new and useful Improvement in Transformers, of which the following is a specification.

The oscillation transformers employed in wireless signaling are frequently so arranged that the lengths of the windings, especially the secondary, may be varied to adapt them for operation at different wave-lengths. As such apparatus has heretofore been arranged, this change has necessitated 15 another adjustment to maintain constant the coefficient of coupling between the primary and secondary. This adjustment has customarily consisted of a movement of these elements toward and from one another, so that 20 as the number of turns in the secondary is decreased the primary and secondary are brought into closer proximity, they being separated if the length of the secondary is increased. This is objectionable, in that 25 while all the other adjustments required for a change of wave-length may readily be obtained by a simple switching of electrical connections, this alteration of the relation of the primary and secondary demands the 30 bodily movement of one of these elements, an action which cannot easily or reliably be accomplished by mechanical connection with the switching means. To depend upon an independent adjustment of the transformer 35 elements throws an undesirable burden upon the operator. The present invention removes the difficulty by providing a transformer possessing a constant coefficient of coupling for all adjustments of the length 40 of its windings.

In the accompanying drawings, Figure 1 shows a top plan view of one embodiment of my invention; Fig. 2 is a side elevation thereof; Fig. 3 illustrates by a set of curves 45 the relation between the radius of a primary winding and the coefficient of coupling for different numbers of turns of the secondary, with the arrangement of transformer previously used; Fig. 4 shows for a similarly ar- 50 ranged transformer the relation between the number of turns of secondary winding and the coefficient of coupling for two primaries of different radii; while Fig. 5 exhibits in a like manner the relations for a trans- 55 former made in accordance with my invention.

Referring to Figs. 1 and 2, upon a suitable frame 10 is carried an insulating support, which in the form of invention I have chosen to illustrate is a disk 11 bearing 60 radial arms 12 containing transverse slots 13 adapted to receive the spirally arranged turns of a flat secondary winding consisting of a conducting ribbon 14. Tapes 15 connect the ends of the secondary and the desired number of intermediate points to co-operating apparatus, which is not shown. The secondary is thus divided into sections, which may be made effective in various combinations to change the length of the wind- 70 ing and therefore its inductance.

Mounted upon the frame 10 opposite the secondary is an insulating spider 16, to the inner side of which is fixed a flat primary 17 of any suitable number of turns of conductor. Clips or connectors 18 permit conductors 19 leading to the associated apparatus to be fixed to the primary at different points so that the effective lengths of these portions now to be described may be varied. 75 This primary 17 consists of two main portions *a* and *b*, preferably in the form of arcs of circles of different radii. *a* is smaller, lying between the inner turns of the secondary and its central turns, while *b* 80 is situated between said central turns and the outer turns. The two arcuate portions are joined by a portion *c* which is generally radial, though its junctures with the portions *a* and *b* are rounded as indicated at *c'* to re- 85 duce the brush discharge. For use in some systems it may be desirable to furnish sectional connections for changing the length of the primary, precisely as has been already described for the secondary. 90

To make clear the effect upon the coefficient of coupling of transformers provided with a single-turn primary of one radius of a change in the number of turns of the secondary, four curves M, N, O and P are 100 shown in Fig. 3, which are plotted with radii of the primaries as ordinates and coefficients of coupling as abscissæ, the curves corresponding respectively to sections of 10, 20, 30 and 40 turns of secondary. It will 105 be seen that for a primary of any particular radius, the coefficient of coupling varies considerably as the turns of the secondary are altered, requiring the adjustment of the distance between the primary and secondary as 110 previously pointed out. In Fig. 4, the two curves Q and R show the relations existing in

the same type of transformer, or that heretofore used, for two primaries of three and seven inches radius respectively, these curves having coefficients of coupling as ordinates and turns of secondary as abscissae. In the present embodiment of the invention the smaller number of turns start at the inside of the secondary winding and increase outwardly, and it will be observed that the primary of smaller radius displays a maximum coefficient of coupling for the fewer turns of secondary, it decreasing as the number of turns of secondary increase, because the added turns are farther removed from the small primary. Of the large primary exactly the reverse is true, the coefficient of coupling increasing as the turns of secondary increase.

A consideration of the curves of Fig. 4, in connection with that of Fig. 5, will make apparent the theory underlying the present invention. If in each turn of the primary there be provided portions of different radii, so that one portion will consist of an arc 25 lying nearer the inner turns of the secondary and another portion of the arc in proximity to the outer turns of the secondary, such an average inductive effect will be obtained that the coefficient of coupling may be made substantially the same for all the adjustments of the secondary. The structural features of a transformer so organized has already been explained in connection with Figs. 1 and 2. The arcuate portions *a* and *b* of the primary 17 by their relation to the inner and outer turns of the sectional secondary 14, give the novel results sought. The variation of the lengths of the primary arcs by movements of the clips 18 facilitate the adjustment of the transformer to give a coefficient of coupling constant in value. The radii chosen for the portions *a* and *b* correspond to those indicated by the dotted lines in Fig. 3. Curves similar in character to those of Fig. 4 plotted from observations made upon such a coil are shown in Fig. 5. It will be seen that the resultant curve approaches closely to a straight horizontal line, all adjustments of the turns of the secondary giving a coefficient of coupling about 0.37.

As it may be desired in the operation of the system in which the transformer is used to change the coefficient of coupling independently of the alteration of the turns of

the secondary, the spider 16 has means for moving the primary toward and from the secondary. This is furnished by a screw 20 journaled to 21 in the frame 10 and having a head 22 by which it may be turned. The inner end of the screw 20 is threaded into the spider so that when the screw is turned the primary may be caused to advance toward or withdraw from the secondary. Pins 23 projecting from the frame through openings in the spider arms prevent rotation of the spider and primary.

I claim as my invention:

1. A transformer having a primary and a secondary winding, and means for varying the effective length of these windings, one of the windings being constructed and arranged to maintain the coefficient of coupling constant during such variation in length. 75

2. A transformer having a primary and a secondary winding, and means for varying the effective length of one of these windings, the other winding being constructed and arranged by its conformation to maintain the coefficient of coupling constant during such variation in length. 80

3. A transformer having a primary and a secondary, and means for varying the effective number of turns in one of these elements, the other element having portions differing in their relation to said turns whereby the coefficient of coupling is maintained constant upon a variation in the turns. 90

4. In a transformer, a winding having each turn consisting of a plurality of portions, each portion being in the form of an arc the radius of which is different from those of the associated portions, external circuit connections for said portions, and means including said connections for varying the effective lengths of the arcs. 95

5. A transformer having a primary and secondary winding, means for varying the effective length of one winding, the second winding consisting of arcs of different radii in order to maintain the coefficient of coupling substantially constant during variation in length of the first winding. 100

Signed at Boston, in the county of Suffolk and State of Massachusetts, this 3d day of May, 1917.

VANNEVAR BUSH.
